GAME APPARATUS

Orville F. Whittle, Miami, Fla., assignor to Roto-bowling Corporation, a corporation of Florida

Application September 19, 1941, Serial No. 411,581

3 Claims. (Cl. 273—37)

The apparatus of the present invention is known as the "Court of Kings." It involves some of the features employed in billiards, such, for example, as elastic cushions and some of the features employed in bowling, but it differs radically from either of these well-known sports because it looks to the employment of power means for propelling relatively heavy balls, such as standard bowling balls or even heavier balls, over courts materially longer than the conventional bowling alleys. It is possible to do this in my invention, because the action of the ball is not limited by the strength of the player. Upon the contrary, the player expends his energy and skill in the art of controlling the power stored in the ball by power means such as an electric motor.

Thus, the ball is capable of much greater and speedier travel than could be secured from manual power alone. This makes it possible to cause the ball to coact with the cushions, hazard pins, etc., through an elongated path much in excess of the length of travel imparted to ordinary manually propelled bowling balls.

Because of the great length and the high speed of travel of balls as large as or even larger than standard bowling balls, and the novel manner of coaction with interposed hazards, elastic cushions and the like, the game which may be played with this apparatus is rendered highly interesting and greatly exceeds in its possibilities anything inherent in conventional bowling apparatus.

Further objects and advantages of the invention will be set forth in the detailed description which follows.

In the accompanying drawings:

Fig. 1 is a side elevation of a court constructed in accordance with the invention;

Fig. 2 is a longitudinal, sectional view through the player's end of the court;

Fig. 3 is a detail, vertical, sectional view through the mounting of one of the hazard pins;

Fig. 4 is a plan view of the player's end of the courts;

Fig. 5 is a plan view of the rear end of the courts;

Fig. 6 is an enlarged, transverse, vertical, sectional view through the two courts, upon an enlarged scale, and;

Fig. 7 is an enlarged, transverse, sectional view through a part of the player's end of the court, illustrating the loading apparatus and power bowling machine, hereinafter described.

In establishing the "Court of Kings," provision may be made for as many units as may be de-

sired. In the particular form illustrated, two units or courts are shown, arranged side by side. Each court is approximately 90 feet in length and comprises any suitable surface.

In Fig. 6, I have illustrated these surfaces as being built up of suitable masonry blocks 5 supported upon a preferably iron bench plate 6. This bench plate is, in turn, supported upon a flat and true metallic plate 7. The blocks 5 may be of any suitable material such as slate, concrete or otherwise, and they may be covered first with Celotex 8, and then with a sheet 8^a of any suitable material, such as broadfelt, rubber or any composition fabric which will be highly resistant to wear and sound-deadening in its nature.

At the target end of the courts, a pit 9 has its floor 10 depressed to lie below the runway of the court in a manner common in bowling alleys, and the rear end of this pit is provided with a conventional backing cushion 11, against which the balls strike in the usual way. The pit is also floored with a conventional rubber mat 12. A conventional pin-spotting device 13, may be employed to spot the pins 14.

By referring to Fig. 6, it will be seen that the sides 14' of the courts upstand above the floors 8 and carry elongated rubber banking cushions 15 and elongated fluorescent tubes 16, said tubes being housed and protected by shade strips 17. These fluorescent tubes not only light the courts substantially throughout their length, but they greatly add to the attractive appearance of the courts as a whole. They may be made to yield soft, colored lights in varying combinations, and the resultant effect is very pleasing. The cushions 15 project far enough beyond the shades 17 so that the balls 18 will contact the cushions without touching the shades.

A space 19 between the courts constitutes a return runway through which the balls may pass from the pit at the pin end of the court to an automatic loading device at the player's end of the court. A strip of wood 20 carrying strips of rubber 21 constitutes a track for the balls in the bottom of the runway and the runway may be covered by a sheet 22 of plywood or any other suitable material.

When the balls have been played and are picked, by the attendant, out of the pit, they are placed upon a runway 23, the tracks of which align with and constitute extensions of the tracks 24 in the runway 19.

At the player's end of the court, the returned balls pass first over a retarding hump 24, then

beneath a ball retarder 25, both of conventional form, and are then discharged into the automatic loading device 26.

As previously stated, the courts of the present invention are intended to be used in connection with power bowling devices and with automatic loading means for loading the returned balls into the power bowling machine, by which the balls are first rotated at a high rate of speed and then discharged along the court toward the pin end thereof. The particular form of power ball propelling means employed in conjunction with these courts is immaterial.

I may use power machines like those shown in my copending application 319,123, filed February 15, 1940, Method of and apparatus for propelling bowling balls, or application Serial No. 323,619, filed March 12, 1940, allowed April 16, 1941, and I may use a loading apparatus conforming in principle to the loading apparatus disclosed in application Serial No. 379,315, filed Feb. 17, 1941, Automatic loader for power bowling machines.

In Fig. 7 I have illustrated a power, ball rotating, machine 27 adapted to receive any one of the balls 18 between the supporting rollers 28 and a power roller 29 driven by an electric or other motor, the housing of which is indicated at 30. As in the apparatus of application, Serial No. 379,315, a ball may be discharged laterally from the loading rack 26 in Fig. 7 by the act of advancing the loading machine toward the loading rack. In this movement, the nose 32 of the power machine or unit contacts an ear 33 upon the underside of an arcuate pan 34 to tip said pan against the action of its spring 35 and thereby cause the contained ball to be rolled over into the power bowling machine.

The apparatus of the present invention differs slightly from the apparatus of Serial No. 379,315 in that each alternate pan 34 is adapted to tip in an opposite direction so that a power bowling machine for one of the courts of Fig. 4 may be loaded from one side of the loading rack, while a corresponding power bowling machine for use upon the other court may be loaded from the opposite side of the loading rack.

Ornamental posts 36 are located at the player's end of the courts and carry the ornamental lamps 37 upon their tops. In addition these posts serve to support a transverse conduit 38 carrying electric wires, not shown, to supply current to said lamps and to the power bowling machine, it being understood that said machines are provided with flexible electric cords such as are commonly used in conjunction with vacuum cleaners and like portable power devices.

A king hazard pin 39 is disposed centrally of each court and is supported by a suitable ornamental framework 40. An ornamental light 41 is supported by the frame 40 and may have the design of a crown in order to carry out the "court of kings" motif. In like manner, joker hazard pins 42 are disposed upon opposite sides of the respective courts at a point preferably in advance of the king hazard pins, being supported upon frames 43 and having associated therewith ornamental lights 44 surmounted by some suitable ornamental design, such as a Greek cross, 45.

The frames 40 and 43 serve as conduits in which the necessary wiring for lights 41 or 44 may be concealed. Annular abutments limit the upward swinging movement of the hazard pins, these abutments being similar to those commonly employed to limit the upward swinging movement

of punching bags. They comprise the rims 46^a and spokes 47 and are supported from the frames 40 and 43.

The hazard pins comprise a wood core 50 having a central opening 51 for the reception of weights 52. The wood cores 50 are covered with a thick band of rubber 54, and this rubber is, in turn, covered with a heavy felt cloth 55. The weights 52 provide means for loading the pins so that their weights will be exactly the same.

The hazard pins and weights are traversed vertically by and supported by rods 60 having eyes 61 at their upper ends. These eyes are engaged by the lower ends of springs 62 hung upon transverse pins 63 movable in slots 64 (only one of which is shown), of pipes 65, said pipes being carried by and depending from frame 40 or 43 as the case may be. The transverse pins may be vertically adjusted to increase or decrease the tension of the springs 62 by nuts 66 threaded for vertical adjustment upon the outside of the pipes. Safety connections 66^a extend between the pins 63 and the eyes 61. These may consist of any suitable flexible members such as chains covered with rubber tubes, and their function is to permit swinging movement of the pins but to keep said pins from flying outwardly if the springs should break. Caps 67 are fastened to the upper ends of the hazard pins and their upper edges engage in recessed portions 68 of heavy metal rings 69 fixed upon the lower ends of the pipes 65.

When the pins are struck by a ball and swung from the vertical, the caps 67 rock upon the rings 69 and the eyes 61 move downwardly, putting the springs under tension. The springs serve to quickly return the hazard pins to the vertical and to prevent excessive swinging of said pins.

If desired, I may arrange electric circuits so that the lights 41, 44 will be lighted or additionally lighted by the striking of the hazard pins. Many ways may be resorted to to accomplish this result, as for example by disposing contacts c in position to be bridged by the eyes 61, when they move downwardly.

It is to be understood that the accompanying drawings are intended to be illustrative only of the principles employed. It is clear that many ways will readily suggest themselves to those skilled in the art of modifying the apparatus in respect to features widely divergent from those herein shown and described. Consequently, I wish it to be understood that the invention includes within its purview whatever changes fairly come within either the terms or the spirit of the appended claims.

Having described my invention, what I claim is:

1. In a court of the character described, an elongated runway, elastic banking cushions extending along the sides of the court in position to be engaged by a bowling ball upon said runway; a pair of joker hazard pins of relatively small diameter suspended for swinging movement at a height to be contacted by the bowling balls and disposed upon opposite sides of the center line of the court, a king hazard pin of considerably larger diameter suspended at the center line of the court and mounted for swinging movement under the impact of the ball, said court comprising an area dimensioned and adapted to receive a group of free pins in the nature of bowling pins at the far end of the court.

2. The combination with a court comprising a runway dimensioned to receive and support bowling balls in motion, of a hazard pin suspended

for swinging movement above said court, said hazard pin comprising a weighted core, a fabric covering and a supporting stem, a spring means engaging said stem and supporting said pin and tending to return the same to vertical position, an annular rim above said pin which limits the upward swinging movement of the pin, and means for adjusting the tension of said spring means.

3. In game apparatus of the character described, an elongated court comprising a relatively flat runway and upstanding sides dimensioned to constitute a trackway for a bowling ball, an elastic cushion extending along each of said sides, substantially throughout the length of the runway, the far end of the court comprising a surface arranged to receive and support a group of free pins of the conventional ten-pin type and the opposite end of the court constituting a

player's area, a pair of joker hazard pins of relatively small diameter arranged as a pair and disposed athwart the runway and equidistantly spaced upon opposite sides of the center thereof, a king hazard pin of materially larger diameter than the joker hazard pins disposed at the center line of the runway at a material distance therealong from the joker hazard pins, all of said hazard pins being suspended above the runway with their lower ends spaced therefrom, said pins being mounted to swing in any direction, springs tending to maintain said pins in a vertical position, means for adjusting the tension of said springs to determine the degree of deflection imparted to the ball by contact with said pins, and means for limiting the upward swing of the pins at all points in their possible travel.

ORVILLE F. WHITTLE.
